CONVERSION OF HYDROCARBONS

Edward W. S. Nicholson, Baton Rouge, La., and Francis R. Russell, Mountainside, N. J., assignors to Esso Research and Engineering Company, a corporation of Delaware

Application September 16, 1953, Serial No. 380,407

1 Claim. (Cl. 196—55)

This invention relates to a process for treating hydrocarbons and more particularly relates to the cracking or coking of heavy residual oils to produce lower boiling hydrocarbons and coke.

The hydrocarbon residual oil which is to be cracked according to the present process is a high boiling hydrocarbon oil which cannot be vaporized at ordinary pressures without cracking the high boiling constituents. The residual oil may be that produced by distilling crude petroleum oil at ordinary atmospheric pressure or under subatmospheric pressure such as vacuum distillation. The present process may also be used for cracking or coking shale oils, pitches, tars, etc.

Processes are known in the prior art for cracking or coking residual oils in the presence of finely divided inert or substantially inert solids maintained as a fluidized bed.

In the present process a dense fluidized bed of finely divided inert refractory solids such as sand, coke, etc., is used and the preheated residual oil is introduced into the dense fluidized bed of finely divided solids maintained at reaction temperature. Vaporous products of coking are taken overhead and further treated as desired to recover lower boiling hydrocarbon fractions. During coking more coke is formed and some coke is withdrawn from the process. Coke particles from the coking zone or reactor are stripped to remove volatile hydrocarbons therefrom. Some of the stripped coke particles are withdrawn as product coke and the rest of the coke particles are passed to a burner where they are preferably maintained in a dense fluidized condition and contacted with air or other oxygen-containing gas to burn some of the coke particles and to supply heat to the coke particles. The heated coke particles are then returned to the coking zone to supply heat thereto. A transfer line burner may be used instead of a more conventional, low-velocity burner in which the particles are maintained in dense phase condition.

One of the problems in the fluid coking of residual or other heavy oil feeds is the control of the particle size of the coke particles in the circulating coke stream. The most desirable particle size range for circulation in the system is that from about 75 to 400 microns. There is a gradual increase in size of the particles being circulated because coke is made from the oil feed and deposited on the particles regardless of size. The coke made from the oil feed is deposited on the particles in a substantially uniform layer. As the circulating coke particles become coarser, fluidization becomes poor, circulation more erratic and contacting efficiency decreases.

The above condition is aggravated by the combustion step in the burner because the smaller coke particles weight for weight have a relatively larger surface than the larger particles and will therefore be more easily burned by the oxygen-containing gas in the burner. It is desirable to remove coke particles coarser than the preferred size range as product coke and by the same token it would be most desirable if the bulk of the heat released

2

for the coking process by coke combustion were obtained from this undesirable coarse particle size range.

The very fine fraction of coke particles, produced by attrition, etc., cannot normally be held in the circulating system and is lost through the cyclone separators or other gas-solid separating devices. In operation of existing equipment, these fines are a complete loss because they are blown out of the top of the burner dense bed under conditions wherein little oxygen is present in the vent gas so that substantially no combustion and heat release or recovery from these fine particles is possible.

Previous coking processes have required withdrawing coarse coke particles from the unit, grinding them and returning the ground particles to the unit. The present invention eliminates the necessity for such grinding of withdrawn coarse coke particles and return of the ground material to the unit.

According to the present invention the larger or coarse coke particles are preferentially burned in the combustion zone or burner by adding a stationary packing material to the burner zone to cause the coarse coke particles to settle to the bottom of the burner zone where the oxygen or air or other oxygen-containing gas is first introduced. At the temperatures normally employed in the combustion zone or burner zone, the oxygen will be consumed and disappear rapidly; in other words, reaction rates will be quite high. Thus very little oxygen will reach the upper levels of the burner or combustion zone where the fine coke particles accumulate and substantially only the coarse particles will react with the oxygen. After the coarse particles have been burned sufficiently, their size is decreased by burning or spalling into smaller coke particles which are carried by the upflowing gas into the upper portion of the burner zone and not consumed further. These smaller coke particles then act as seed coke and also improve fluidization and mobility of the circulating stream of coke particles.

In a more specific form of the invention, provision is made for burning fines normally lost from the unit and recovering heat therefrom for the process. Coke particles from the reactor or coking unit are mixed with a controlled amount of air ahead of or after a cyclone separator, and in the cyclone separator coarser solids are separated from fines which pass overhead. Combustion of the fines takes place in the overhead line. The hot fines are returned to the upper portion of the burner zone where they are mixed with and add heat to hot coke particles being returned to the coking zone. The mixture leaving the burner is passed through a gas-solids separator device, the separated hot solids being returned to the coking unit while the burned fines are lost with the gas leaving the separator.

In the drawing the figure represents one form of apparatus adapted for carrying out the present invention but this showing is for purposes of illustration only and the invention is not to be restricted thereto.

Referring now to the drawing, the reference character 10 designates a reactor or coking zone containing a fluidized dense bed 12 of solid finely divided inert particles such as coke or the like. The dense bed 12 has a level indicated at 14 with a dilute or disperse phase 16 thereabove. The inert solids of the fluidized bed 12 have a particle size between about 20 and 800 microns, preferably between about 75 and 400 microns and may comprise petroleum coke, or other coke, coke formed in the process, spent cracking catalysts, pumice, Carborundum, alumina or other refractory materials.

The fluidized bed 10 is maintained at a temperature between about 800° and 1600° F., preferably about 900° to 1100° F.

When coking to produce motor fuel such as gasoline,

temperatures in the lower range of about 800° to about 1200° F. will be used, whereas, when coking at extremely high temperatures to produce chemicals such as unsaturated hydrocarbon gases and aromatic hydrocarbons, temperatures in the higher range of about 1200° F. to about 1600° F., preferably about 1250° to 1450° F., will be used.

The preheated oil feed to be converted may be introduced directly into the dense fluidized highly turbulent bed 12 in the reactor or it may be introduced through feed line 18 into riser 22 for distributing the oil feed on the hot inert solids coming from the burner as will be later described in greater detail. Steam and/or feed may be introduced through line 18. If steam alone is passed through line 18, the oil feed may be introduced further along line 22 through line 23. In some cases it may be desirable to feed or spray the oil feed into the dilute phase 16 above the dense bed level 14. The oil feed is preferably preheated in any suitable manner to a temperature between about 600° and 800° F. before being introduced into the reactor 10. The oil feed comprises a residual petroleum oil such as tar, pitch, crude residuum, heavy bottoms or other similar hydrocarbon stock having an API gravity between about 10 and 20°, a Conradson carbon between 5 and 50 wt. percent and an initial boiling point between about 850° and 1200° F. Steam may be introduced at one or more points 24 to assist in maintaining the bed in fluidized condition.

The fluidized bed 12 is maintained as such by the upflowing hydrocarbon gases and vapors formed by the coking of the oil feed and by the steam added to the process. The superficial velocity of the gases and vapors passing upwardly through the bed 12 is between about 0.5 and 4 feet per second when using finely divided coke of about 50 to 400 microns and at a superficial velocity of about 1 to 2 feet per second, the density of the fluidized bed will be about 40 lbs. per cu. ft. but may vary between about 15 and 60 lbs. per cu. ft. depending on the gas velocity selected and the particular particle size range.

Vaporous products of coking leave the bed 12 and pass overhead into inlet 26 of cyclone separator 28 arranged at the top interior of the reactor 10. The vaporous reaction products leaving the coking zone contain entrained solids and the cyclone separator 28 or other gas-solids separating device is used to separate or recover the entrained solids and return them to the dense fluidized bed through dipleg 32. More than one cyclone separator in stages may be used and the cyclone separator or separators may be arranged externally of the reactor 10.

The separated reaction vapors pass overhead from the cyclone separator 28 through line 34 and are further treated in any suitable manner to recover gas, gasoline, gas oil, etc.

Coke particles are withdrawn downwardly from the dense bed 12 into stripping zone or vessel 36 which is shown as having a smaller diameter than reactor 10 and which extends down from reactor 10 as an integral structure. Other forms of stripper may be used. Steam or other stripping gas is introduced through line or lines 38 into the bottom portion of the stripping zone 36 to remove volatile hydrocarbons from the coke in the stripping zone and pass them upwardly into the dense fluidized bed 12 in reactor 10. The temperature in the stripping zone is between about 800 and 1600° F. and the velocity of the upflowing gas in the stripper may be between about 0.4 and 2.0 feet per second to maintain a dense fluidized mixture.

Stripped coke particles are removed from the bottom of the stripper through line 42 to which fluidizing gas may be added through one or more lines 44. Line 42 is formed as a U-bend 46 and the solids therein are maintained in a fluidized condition. Operation of U-bends is described in Packie Patent 2,589,124 granted March

11, 1952, and a further description is not necessary here. Gas such as steam or the like in a small amount is added at the bottom of the U-bend 46 as at 48 to maintain fluidity of the solid particles.

5 According to one method of operation according to the present invention and in order to reduce or remove the coarse coke particles in the circulating stream which are formed by successive layers or deposits of coke on the particles during the coking process, the coke particles in U-bend 46 are passed through riser 52 into the lower portion of a packed elutriator-burner 54. As above pointed out the coke particles increase in size because of the formation and deposition of more coke on the coke particles in the circulating stream and these 10 coarse particles having a particle size bigger than about 500 to 1000 microns must be removed or somehow reduced in size if they are to remain in the unit. According to the present invention the coarse particles are selectively burned to remove them or to make smaller particles within the desired range of 75 to 400 microns.

15 The upflow leg 52 of U-bend 46 is provided with a variable restriction such as a slide valve 56 to assist in the control of circulation of solids. Steam or the like is introduced into riser 52 through line 58 above restriction 56 to control the rate of flow of solids to burner 54. Upflow leg 52 empties into the lower portion of the burner 54 but preferably above the bottom thereof. If desired, leg 52 may empty into burner 54 at a higher level than shown in the drawing.

20 30 Air or other oxygen-containing gas is introduced through line 62 into the bottom portion of burner 54 below the locus of introduction of the coke particles passing through line 52 to preferentially burn the coarse coke particles collected in the bottom of burner 54 by elutriation. At the temperatures normally employed in the burner 54, the oxygen in the gas introduced through line 62 will be consumed and disappear rapidly and very little oxygen-containing gas will reach the upper levels of the burner 54 where the fine particles accumulate. 35 Most of the oxygen will be consumed in the first few feet of travel through the coke bed in the burner in cases where the temperature is between about 1000° and 1700° F.

40 45 The elutriating burner 54 is packed with a non-fluidizable material such as Berl saddles, Raschig rings, baffles of various shapes, spaced chains hanging down through the bed, etc., the packing being diagrammatically shown by cross hatching 64. For a burner having a diameter of about 5 to 20 feet, Berl saddles of about 1/2 to 4 inches may be used. The superficial velocity of the upflowing gas in burner 54 is between about 2.0 and 6.0 ft./sec. and is sufficient to carry overhead through line 66 the middle-sized and finer particles. The particle size of the solids going overhead is about 50 to 400 microns.

50 55 The gaseous suspension passing overhead through line 66 is introduced into gas-solids separating means 68 such as one or more stages of cyclone separators. The separated combustion gases pass overhead through line 72 and the separated solids are passed to standpipe 74 which may have one or more fluidizing or aerating lines 76. Standpipe 74 forms one leg of another U-bend 78 having a bottom aeration line 82 through which gas such as steam is introduced in amount sufficient only to maintain the solids in a fluidized condition in the U-bend 60 78. The riser 22 (previously referred to) of U-bend 78 has a valve 84 or other variable restriction orifice to assist in controlling the flow of the circulating solids. The function of restriction 84 is the same as that above described for restriction 56.

65 70 Some of the hot coarse solids may be withdrawn from the bottom portion of burner 54 through line 86 and introduced into U-bend 78 for recycle to coking bed 12, if desired. Some of the hot coarse solids may be withdrawn from line 86 through line 88 as product 75 coke after proper cooling or quenching.

In a more specific form of the invention, provision is made for preferentially burning fines and recovering heat from these particles which are usually lost from the system. In addition provision is made for burning the coarse coke particles in elutriating burner 54 as above described in connection with the broader form of the invention. In this specific form solids from U-bend 46 are passed through riser 92 provided with a valve or other restriction orifice 94 rather than through line 52. Steam or other gas is introduced into riser 92 above valve 94 through line 95 and the amount of steam introduced controls the rate of flow of solids through riser 92. Ahead of cyclone separator 96 or other separating means, a gas stream containing a controlled amount of oxygen may be introduced through line 98 into riser 92. In separator 96 the bulk of the solids is removed and the fines and gas pass overhead through line 102. Burning of the fines or fine fraction of the circulating stream is started and continues in the overhead line 102 containing the fines and the oxygen-containing stream.

The quantity of oxygen introduced into this fine particle system is so regulated that there will be essentially no oxygen remaining at the outlet of line 102 where it opens into the upper portion of the burner 54. Overhead line 102 is elongated to permit time for burning a substantial fraction of the fines stream and particularly the smaller particles in this stream. Line 102 is shown as an inverted U-bend but may take other forms.

Instead of introducing the oxygen-containing gas through line 98, gas containing no oxygen may be introduced through line 98, or introduction of gas at this point may be eliminated entirely, and air or other oxygen-containing gas in controlled amount added to line 102 through line 104, if it is desired to eliminate any possibility of burning coarser particles in this part of the system.

The coarse fractions of the circulated solids separated out in the cyclone separator 96 and containing particles larger than about 50 to 100 microns, are passed down through standpipe 106 which may be provided with one or more fluidizing or aerating lines 108. Standpipe 106 forms part of U-bends 109 and 110 which are similar in construction and operation to the U-bends previously described.

Upper U-bend 109 has bottom fluidizing line 112, variable restriction 114 in riser 115 and a line 116 for introducing a gas above restriction 114 for controlling flow of solids through riser 115. The gas introduced through line 116 is preferably a gas such as steam. Riser 115 opens into an intermediate portion of burner 54 above the outlet of riser 52 of U-bend 46 above described. As above described, oxygen-containing gas such as air is introduced through line 62 into the bottom of elutriating burner 54.

Lower U-bend 110 has aerating bottom line 118, riser 120, variable restriction 122 and gas introduction line 124 above restriction 122. Gas such as steam is introduced into riser 120 through line 124 for control purposes. Gas in line 124 may contain oxygen.

The U-bends 109 and 110 may both be used so that solids from standpipe 106 pass both into the bottom portion and intermediate portion of burner 54 or only one U-bend may be used for introducing such solids either into the bottom portion of burner 54 or into an intermediate portion of burner 54.

In the elutriating burner 54 a controlled quantity of air is introduced through line 62 and the superficial velocity of the gases flowing up through burner 54 is selected to be between about 2.0 and 6.0 feet/sec. so that middle-sized coke particles of about 75 to 400 microns are elutriated overhead without substantial combustion of these particles. The coarsest particles (approximately 400 to 1000 microns) fall to the bottom

5 of the burner 54 and are retained there, and consume by combustion essentially all the oxygen which is introduced into the bottom of the burner 54 through line 62. During burning of the coarse particles in the bottom of burner 54, the coarse particles are reduced in size and become fine enough to be moved up in the elutriating burner for recycle to the coking zone. During burning some of the coarse coke may spall or otherwise break down into smaller pieces.

10 The middle sized particles are elutriated overhead from the burner without substantial loss due to combustion. The elutriated particles pass through line 66 above described and then through cyclone separator 68 for recovery of hot solids which are returned to coking zone 12 through U-bend 78. The hot gas and fine coke or ash particles leaving the fines burner line 102 are combined with the elutriated middle size particles from elutriating burner 54 at the top of the burner 54 or by being introduced into line 66 leading to final cyclone separator 68 so that the heat available in the gas-fines stream is recovered by the middle size particles recovered in cyclone separator 68 for circulation back to the coking zone 12. The burned fines are lost to the atmosphere through line 72 leading overhead from cyclone separator 68. The middle size particles leaving the top of the burner 54 are essentially unburned but they are heated by contact with hot particles and by the hot combustion gases passing up through the burner 54. The hot combustion gases are formed by burning the coarse coke particles at the bottom of burner 54.

15 In this form of the invention a circulating solids stream of an optimum particle size is maintained while obtaining all the heat necessary for the coking operation by selectively or preferentially burning the undesirable fine and coarse fractions of the coke. Some hot coarse particles may be withdrawn through line 86 from the bottom of burner 54 and introduced into line 74 containing middle sized particles for supplying additional heat to the particles being returned to coking zone 12.

20 During combustion of the coarse coke particles in the burner 54 the temperature is between about 1000° and 1700° F. Additional heat is added to the medium sized particles from the fines burned in line 102 so that the particles being recycled to coking bed 12 through U-bend 78 are at a temperature between about 1100° and 1750° F. and contain sufficient heat to vaporize and crack or coke the feed oil introduced into coking zone 12.

25 In cases where more heat is required than is being produced by burning coke in burner vessel 54, oil or gas or other fuel may be introduced into vessel 54 through line 128 or hot combustion gases may be supplied to burner 54.

30 In a specific example about 100 barrels per day of residual oil having an API gravity of 10° and a Conradson carbon of 18 and an initial boiling point of about 1150° F. and about 7000 lbs. per day of steam are added to the the dense bed 12 in reactor 10. The oil feed is pre-heated to about 600° F. The solids to feed oil ratio by weight to the reactor is about 15 to 1. The temperature in the reactor is about 1000° F. and in the burner is about 1150° F. About 2 to 3 gallons per hour of oil are injected into the burner 54 through line 128 to provide for heat losses in this small pilot plant.

35 The circulating solid is coke formed in the process having a particle size of about 50 to 800 microns with the majority of the particles being between about 150 and 300 microns. The superficial velocity of the gas in the reactor 10 is about 1 ft./sec. at the bottom of the cylindrical portion and the density of the dense fluidized bed 12 is about 45 lbs./cu. ft. The superficial velocity of the gas in the burner 54 is about 3 ft./sec. and the density of the dense fluidized bed 55 is about 40 lbs./cu. ft.

40 The stripper 36 is at a temperature of about 995° F. and

7
the superficial velocity of the stripping steam passing upwardly through the stripper is about 1.0 ft./sec.

The overhead products leaving cyclone separator 28 through line 34 are at a temperature of about 1000° F. and are quenched to a temperature of about 800° F.

The yields obtained are as follows:

C ₃ , wt. percent	6.5
C ₄ , vol. percent	2.8
C ₅ —430° F., vol. percent	15.0
430—650° F., vol. percent	10.7
650—1050° F., vol. percent	30.0
1050° F. +, vol. percent	30.0
Coke, wt. percent	10.0

About 65 lbs. of coke per hour are withdrawn as product coke through line 88.

Coke particles from line 52 are introduced into the lower portion of burner 54 but above the bottom thereof to effect elutriation of the coke particles in the burner 54 packed with Berl saddles. Air is introduced into the bottom of the burner through line 62. The coke particles going to elutriating burner 54 through line 52 have a particle size between about 50 and 800 microns with about 30 to 50% by weight of finer particles having a particle size between 50 and 200 microns and about 5 to 15% by wt. of coarse particles having a size between about 300 and 800 microns.

In the elutriator burner the finer particles of the desired size between about 50 and 400 microns pass upwardly through burner 54 and the coarse particles larger than about 400 microns fall to the bottom of the burner 54 where they are preferentially burned with air introduced through line 62. Most of the oxygen is quickly consumed in a few feet of travel (about 4 feet) in burner 54 so that substantially none of the finer particles of the desired particle size are burned but they are heated by the combustion gases flowing up through the burner formed by burning the coarse coke particles in the bottom of the burner 54. For about 70 lbs. of coke burned off the coarse particles per hour about 750 to 900 lbs. of air per hour are used and there is substantially no oxygen in the overhead stream in line 66. During burning, the coarse particles are reduced in size and when they become small enough they are entrained with the upflowing gas through line 66 and returned to the coking zone 12 through U-bend 78. Also during burning of the coarse coke particles, spalling or breaking up of the particles to smaller particles may occur.

With the present invention it is possible in most cases to maintain the proper size of coke particles in the circulating coke stream without the necessity of withdrawing coarse coke particles, grinding them and then returning the ground particles to the circulating coke stream.

Instead of passing the coke particles from U-bend 46 to burner 54 directly, they may be passed through riser 92 to cyclone separator 96 to separate fines having a particle size about 75 microns or less. The fines are mixed with air through line 104 to burn them and re-

cover heat therefrom. For about 50 lbs. to 800 lbs. per hour of fines passing through line 102, a limited quantity of air, that is, about 100 to 400 lbs. of air per hour is introduced through line 104. The fines stream 5 at a temperature of about 1100° to 1800° F. and with no free oxygen is passed to the top of burner 54 to supply heat to the middle sized particles leaving the elutriator burner 54 overhead.

The coarser coke fraction having a particle size large-10ly between 75 and 800 microns is withdrawn from cyclone separator means 96 and passed through U-bend 109 to an intermediate portion of elutriator burner 54 wherein the coarse particles settle to the bottom and are burned as above described and the middle sized particles or particles 15 having the desired particle size range go overhead from burner 54. The burned fines and middle sized particles pass overhead through line 66 to separator 68 where fines are lost overhead and the desired size particles are recycled to the coking zone 12.

Instead of passing all the coarse solids from standpipe 106 through U-bend 109, all or part of the coarse solids from standpipe 106 may be passed through U-bend 110 into the bottom portion of burner 54.

What is claimed is:

25 A method of coking a heavy residual hydrocarbon which comprises the steps of contacting a heavy residual hydrocarbon oil with a dense bed of fluidized coke particulate solids in a coking zone maintained at coking temperature by hot coke solids recycled from a burning zone to the coking zone, the coking reaction being accompanied by the deposition of coke on the solids and increase in size thereon; removing vaporous reaction products overhead from the coking zone; removing coke solids from the coking zone; passing an oxygen-contain-30ing gas through the coke solids and selectively removing therefrom coke fines having a diameter of less than about 75 microns; burning these coke fines in the form of a confined stream in the oxygen-containing gas; passing the residual coke particles having a particle diameter larger than about 75 microns and from which the fines have 35 been removed to the lower portion of a packed burning zone; passing an oxygen-containing gas into said lower portion and through the burning zone to selectively burn substantially only particles having a diameter larger than about 400 microns and entrain particles having a diameter of about 50 to 400 microns; removing the thus heated 40 50 to 400 micron diameter particles entrained in gaseous products of combustion overhead from said burning zone; co-mingling the products of combustion from the coke fines burning step therewith; separating combustion gases from the combined stream and returning the remaining heated coking particles to said coking zone.
